UNITED STATES PATENT OFFICE.

PAUL SEILER, OF SAN FRANCISCO, CALIFORNIA.

ANNUNCIATOR SYSTEM.

SPECIFICATION forming part of Letters Patent No. 364,444, dated June 7, 1887.

Application filed September 16, 1886. Serial No. 213,759. (No model.)

To all whom it may concern:

Be it known that I, PAUL SEILER, a citizen of the United States, and a resident of San Francisco, in the county of San Francisco and State of California, have invented certain new and useful Improvements in Annunciator Systems, described, claimed, and shown in the following specification, claims, and drawings.

5 My invention relates to a system of signals adapted especially for use in hotels, large residences, and similar buildings.

The principal object in view is to economize space in the office and to provide simple, effective, and superior means whereby the person in attendance at the office may return a guest's call.

In order to illustrate the practical manner of carrying out the invention, and to enable others skilled in the art to which the invention 20 appertains to make and use the same, drawings are hereunto annexed and described, in which similar letters represent corresponding elements and in which each part referred to is designated by a single character.

25 Figure 1 is a general view of a portion of the system, shown mostly in diagram; and Figs. 2 and 3 show a suitable form of annunciator-drop to be employed in the system. Fig. 4 shows a modification.

30 The system consists of the combination of an annunciator-board, A, provided with the figures 1, 2, 3, 4, 5, &c., in this case arranged in natural order from left to right up to 65, in five horizontal lines and thirteen columns, annunciator drops B, located above each column, and other drops, C, at the left of each horizontal line, floors D of any building—such as a hotel—a central office, E, including said board, said annunciator-drops, and also a signal-bell, 35 F, electric batteries G, and contact-keys H, other bells, I, and keys J upon each floor, and electric circuits, including all of said keys, bells, and annunciator-drops.

Normally the circuit from any battery G 40 passes by a wire, as K, to one of the keys J, and from there through one of the bells I, and back to the battery from which it started through one of the keys H; but when any key J—for example, that in room 53—is depressed the circuit passes from the battery 45 through the depression-key, through one of the

annunciators B, (shown in this instance at a,) through the bell F, through one of the annunciators C, and through the key H back to battery.

55 The closing of the circuit by means of the key J, as above described, causes the bell F to sound. An operator at the office thereupon actuates that particular key H which is connected with the bell in room 53, causing the current to pass through the bell I in the said room, through the key J in that room, and back again to battery. It is of course understood that the key J after release resumes its original position. As soon as the bell I is operated 60 the occupant of room 53 knows that his signal has been received.

The rooms 1, 14, 27, 40, and 53 each represent any room, respectively, on the first, second, third, fourth, and fifth floors. Taken together they represent what may be called a "section," so that when the annunciator marked a drops, one of the rooms in this section calls the office. The particular room of that section is indicated by one of the annunciators C—that is to say, the annunciators C represent the different floors or stories in a hotel or other structure. The annunciators B represent different rooms arranged above one another in the same structure. Any one of the 70 annunciators B may stand for four or five or more different rooms. It is only by reading the two annunciators together that one can know which of the numbers is represented. Thus, the annunciator marked a may stand 75 for 1, 14, 27, 40, or 53. If, however, the lowermost of the annunciators C drops at the same time with the annunciator marked a it indicates that room 53 has called.

80 There are other sections (not shown, as the construction is exactly the same) connected in order with the remainder of the annunciator-drops B, and there are other series of keys exactly similar to H in electrical connection with the remaining batteries and with the 85 keys J. Only one section, one series of keys H, and one battery are shown in circuit, for the sake of preventing confusion.

Fig. 3 is a full front view of either annunciator B or C, for they are substantially alike, 90 and Fig. 2 is a detail view. It consists of the combination of the drop proper, L, weighted

by a projection, M, and held in position by a piece, N, elastically connected with a core, O, of a solenoid, P, located in any circuit, K. When a current passes through the solenoid, 5 the drop is released by the piece N and falls into the position indicated in dotted lines. By means of the string Q it may be pulled again into its normal position. The part R, connecting the drop to the piece N, is hinged 10 in such a manner that it will turn upward but not downward. There are as many batteries G as there are floors.

The invention is not limited to the precise construction hereinbefore described and 15 shown, as it is evident that many modifications may be made therein without departing from the spirit of the invention.

The keys H may be behind the numbers on the board, so that by pushing the numbers, or 20 rather the disks on which the numbers are recorded, the keys will operate. The said disks would be attached to the upper ends of the keys H. This construction is shown in Fig. 4. a, b, and c represent similar parts in Figs. 25 1 and 4. When the disk R is pushed as a push-button, contact is broken at b and made at a. When made at a, a corresponding floor-bell rings to notify the guest that the attendant is aware of a call.

30 Having now described my invention, what I claim, and desire to secure by Letters Patent, is—

1. In a hotel annunciator and alarm system, the combination, with a series of movable annunciating disks or plates numbered to indicate different rooms, and electro-magnetically-operated drops controlled by push-buttons in the different rooms for designating any one of the series of disks or plates, of a series of contacts operated by the movements of the said disks or plates, and electro-magnetic bells in the various rooms in circuit with the said disks and contacts, whereby any one of the disks may be designated by the annunciator-drops, 45 and whereby a return-signal can be sent by depressing the designated disk, substantially as set forth.

2. In an annunciator system, the combination of a table or board of figures arranged in horizontal lines and vertical columns, an annunciator above each column and at the end of each line, a bell adjacent to said board, a series of keys or switches for each vertical column, an electrical generator for each horizontal line, said elements being in the office of a building, floors of a building, electric bells and keys on each floor, and electric circuits passing from said batteries through said last-named or floor keys normally closed upon their back-stops, through said last-named or floor bells, 55 through said first-named keys normally open, and back to said batteries, there being a branch circuit open upon the front-stop of said floor-keys, and passing through the office-bell, through the annunciators, through the office-keys normally closed, and finally back to the batteries, substantially as described.

3. In a signal system, the combination of an annunciator-board having a horizontal line of characters, such as numerals, and a vertical line of characters indicating the numbers of the several rooms of a building, an annunciator drop for each vertical line or column, an annunciator for each horizontal line, one battery for every horizontal line, (there being as 75 many horizontal lines as floors in said building,) an electric bell adjacent to said board and other similar bells, one in each room, one series of keys for each floor adjacent to said board, other keys and bells in each room, and 80 a circuit passing from each battery and normally open through said keys, said annunciator-drops, and said bells, substantially as and for the purpose described.

In testimony whereof I have hereunto signed 85 my name in the presence of two subscribing witnesses.

PAUL SEILER.
